[57] ABSTRACT

In a filter press wherein a plurality of recessed filter plates are so arranged that the plates can be assembled and separated, a pair of filter elements are provided to each filter plate, each of said elements comprising a filter cloth covering the front or rear bed of the plate, upper and lower cloth-supporting bars which are secured to the upper and lower edges of the cloth, and first and second pairs of flexible elongated driving media such as belts, chains or the like which are secured to said supporting bars. Below the plate, the pair of filter elements are trained over guiding rollers so as to come close to each other. The filter elements may be driven to travel through said driving media by driving means provided above the plate in such a manner that said upper and lower supporting bars are moved upwardly and downwardly in a see-saw-like manner. Cakes accumulated on the cloths may be discharged on the way of downward travels of the cloths very easily.

FILTER PRESS

BACKGROUND

This invention relates to a novel and improved filter press of the so-called recessed plate type wherein a plurality of filter plates having recessed cloth-supporting beds on both surfaces thereof are so arranged between front and rear machine frames that the plates can be assembled and separated.

The other type of filter press is the plate and frame type filter press wherein filter frames and filter plates are arranged alternately between front and rear machine frames in such a manner that the filter frames and plates can be assembled and separated. The former filter press is superior to the latter filter press in that the former press may employ more filter plates than the latter press due to the lack of filter frames, the former press thereby having larger filtering area than the latter press. Further, the latter press is larger in numbers of parts or accessories and is more complicated in construction than the former press.

A problem with the recessed plate type filter press according to the prior art, however, is that discharging of cakes is very hard due to the so-called center-feed system for feeding liquid or slurry to be filtered in which system the center of each filter cloth is fixed to filter plate. That is, in the filter press having the center-feed system, discharging or removal of cakes is carried out by, for example, giving vibration to the filter plates or the filter cloths. Due to the fact that such discharging mechanism is complicated and the center of each filter cloth is fixed to filter plate, in the recessed plate type filter press according to the prior art the cakes-discharging operation is hard and the removal of cakes can be achieved only when the filter plates are separated to give considerable intervals therebetween. Further, in the prior recessed plate filter presses washing of the filter cloths while remaining on the filter plates is difficult. The filter cloths can be completely washed only when the cloths are taken away from filter plates, and this requires considerable time. As to the washing of the filter cloths, a known method is supplying washing water against the outer surface of a filter cloth to which surface cakes have adhered. This method is, however, very disadvantageous because impurities and particles in the cakes are forced into the cloth by the washing water.

SUMMARY

Accordingly, it is a primary object of the present invention to provide a novel and improved recessed plate type filter press which permits an easy discharging or removal of cakes from the surfaces of filter cloths.

Another object of the present invention is to provide a recessed plate filter press wherein cakes are removed in a time-saving manner and in a very smooth manner.

Still another object of the present invention is to provide a filter press of said type wherein cakes may be removed or discharged perfectly from the surfaces of filter cloths with ease.

A further object of the present invention is to provide a filter press of said type wherein the cakes-discharging operation does not cause the filter cloths or the cakes thereon to contaminate the filter plates during said operation.

A still further object of the present invention is to provide a filter press of said type wherein filter cloths may be washed easily and smoothly if required.

DESCRIPTION OF THE DRAWING

The present invention will become more readily apparent as the specification is considered in conjunction with the accompanying drawings in which

FIG. 1 is a side elevational view, partially omitted, of the first embodiment of the filter press according to the present invention;

FIG. 2 is an enlarged side elevation view, partially in section and partially cut away, of a part of the filter press shown in FIG. 1 showing a state where filter plates are separated;

FIG. 3 is a front elevational view, partially cut away, seen from arrows III—III of FIG. 2;

FIG. 4 is a perspective view, partially cut away, of filter elements employed in the filter press shown in FIG. 1;

FIG. 5 is a front elevational view, partially cut away, of a filter plate employed in the filter press shown in FIG. 1;

FIG. 6 is a sectional view, partially cut away, of the filter plate taken along line VI—VI of FIG. 5;

FIG. 7 is a sectional view, partially cut away, of the filter plate taken along line VII—VII of FIG. 5;

FIG. 8 is a sectional side view of a part of the filter press shown in FIG. 1 showing a state where filter plates are assembled;

FIGS. 9a and 9b are sectional side views, partially cut away, of two adjacent filter plates showing cakes-discharging operation in the filter press shown in FIG. 1;

FIG. 10 is a side view of two adjacent filter plates showing cakes-discharging operation in the filter press shown in FIG. 1;

FIG. 11 is an enlarged sectional side view of a part of the filter press shown in FIG. 1 showing a state where slurry-feeding device is washed;

FIG. 12 is a side elevational view, partially omitted, of the second embodiment of the filter press according to the present invention;

FIG. 13 is an enlarged side elevational view, partially in section, of a part of the filter press shown in FIG. 12 showing a state where a filter plate is separated;

FIG. 14 is a rear elevational view, partially cut away, seen from arrows XIV—XVI of FIG. 13;

FIG. 15 is a perspective view of filter elements and a slurry-feeding device employed in the filter press shown in FIG. 12;

FIG. 16 is a side view of a cloth-supporting frame and a pair of filter elements employed in the filter press shown in FIG. 12 showing a state where cakes are discharged;

FIG. 17 is a sectional side view, partially cut away, of a part of the third embodiment of the filter press according to the present invention showing a state where a filter plate is separated;

FIG. 18 is a rear elevational view, partially cut away, seen from arrows XVIII—XVIII of FIG. 17;

FIG. 19 is a perspective view of a pair of filter elements employed in the filter press shown in FIG. 17;

FIG. 20 is a perspective view of a slurry-feeding device employed in the filter press shown in FIG. 17;

FIG. 21 is a perspective view of filter elements partially cut away, showing a change in construction of fil-

ter elements employed in the filter press according to the present invention;

FIG. 22 is a perspective view of a pair of filter elements employed in the fourth embodiment of the filter press according to the present invention;

FIG. 23 is a perspective view partially cut away, showing a part of the fifth embodiment of the filter press according to the present invention;

FIG. 24 is an enlarged sectional view of a part of the filter press shown in FIG. 23; and

FIG. 25 is a sectional side view of a part of the filter press shown in FIG. 23 showing a state where cakes are discharged.

DESCRIPTION OF SPECIFIC EMBODIMENTS

Referring now to the drawings wherein like numerals designate like parts throughout the several views thereof, there is shown a first preferred embodiment of the filter press according to the present invention in FIGS. 1 through 11. The filter press includes a pair of guiding rails 1 which are secured to front and rear machine frames 2 at their ends. As is usual, a plurality of recessed filter plates 3 are arranged between a fixed head 4A, which is fixed to the front frame 2, and a movable head 4B which is moved along the rails 1. Each of the filter plates 3 and the movable head 4B are slidably mounted on the rails 1 by means of arms 5 at both sides and are connected to the adjacent plates by a plurality of upper and lower links 6 and 7 having elongated apertures 6a and 7a at both end portions into which pins 8 and 9 projected from the sides of each filter plate and movable head are inserted. All of the plates 3 may therefore be separated at the same time to give definite intervals therebetween by moving the movable head 4B toward the direction of arrow F shown in FIG. 1 and may be assembled again by moving the head 4B toward the reverse direction of arrow F. The movable head 4B is moved by means of a hydraulic cylinder unit 10.

A pair of filter elements which are provided to each filter plate 3 are explained with reference to FIGS. 2 to 4. Each of the filter elements comprises a filter cloth 11A or 11B which covers front or rear cloth-supporting bed 3a or 3b of the plate 3, upper and lower cloth-supporting bars 12 and 13 which are secured respectively to the upper and lower edges of said cloth 11A or 11B, and chains 21 which are secured respectively to both ends of said upper and lower cloth-supporting bars 12 and 13. In the filter press of the present embodiment, a common upper supporting bar 12 is secured to the upper edge of cloth 11B covering the rear bed 3b of a particular plate 3 and to the upper edge of cloth 11A covering the front bed 3a of the next rearward plate 3. That is, the upper edges of filter cloths 11A and 11B disposed between each adjacent filter plates are supported by a common upper supporting bar 12.

The pair of filter cloths 11A and 11B provided to each filter plate 3 are trained respectively over guiding rollers 14 and 15, which are rotatably supported by a pair of brackets 16 projected downwardly from the plate 3 at both sides, in such a manner that cloth 11A covering the front bed 3a of a plate and cloth 11B covering the rear bed 3b of the plate are brought or come close to each other. Therefore, filter cloths 11A and 11B which are disposed between adjacent filter plates 3 and are secured to a common upper supporting bar 12 at the upper ends are trained over guiding rollers 15

and 14 below said two adjacent plates 3 in such a manner that said cloths 11A and 11B are brought apart from each other. Further, in the filter press of the present embodiment, a common lower supporting bar 13 is secured to the lower edge of cloth 11A covering the front bed 3a of each plate 3 and to the lower edge of cloth 11B covering the rear bed 3b of said plate 3. That is, the lower edges of the pair of filter cloths 11A and 11B are supported by a common lower supporting bar 13 which is located above the roller 15 and between the back of brackets 16 and the cloth 11B.

The filter cloths 11A and 11B are driven to travel between the filter plates by driving means which will be detailed hereinafter. The upper portion of each filter plate 3 is provided with an upwardly projected bracket 17 at one side and an upwardly and laterally projected bracket 18 at the other side in such a manner that the brackets 17 and 18 are alternately positioned on the left and right sides on adjacent filter plates. Above each filter plate 3 is provided a driven shaft 19 which is supported by the brackets 17 and 18. On the shaft 19 is fixedly mounted at both sides a pair of sprocket wheels 20 which train a pair of the chains 21. One end of each of the chains 21 is guided through the clearance before each filter plate 3 and secured to one end of said upper supporting bar 12, whereas the other ends of the chains 21 are guided through the clearance behind each filter plate 3 and connected to the ends of said lower supporting bar 13 through a tensioning means comprising a threaded rod 22 and a nut 23 (see FIG. 4). The chains 21 are guided toward the clearance behind the filter plate 3 by rollers 24. On the driven shaft 19 is fixedly mounted at the left or right end (at the side of the bracket 18) a bevel gear 25 which meshes with a bevel gear 26. The latter gear 26 has a key (not shown in the drawings) engaging a spline groove 28 on one of driving shaft 27 bridged between the front and rear machine frames 2, and boss portion 26a of the gear 26 is rotatably received by the bracket 18 so that the gear 26 is slideable but not rotatable on the driving shaft 27. Accordingly, when the driven shaft 19 is rotated by the driving shaft 27 into one or the other direction, the pair of filter cloths 11A and 11B are driven to travel downwardly and upwardly in such a manner that the upper and lower supporting bars 12 and 13 are lowered and raised in a seesaw-like manner.

As shown in FIGS. 5 to 7, each filter plate 3 employed in the filter press of the present embodiment comprises a pair of frame members 29 in the form of picture-frames, a frame-like spacer 30 which is arranged between the members 29, a partition 31 which is arranged in the spacer 30 between the pair of frame members 29, and a pair of diaphragms 32 of a flexible and resilient material such as rubber, softer synthetic resin, or the like which are arranged before and behind the partition 31 and are supported in an air-tight manner by the inner edge portions of the frame members 29 and the outer edge portions of the partition 31. The diaphragms 32 have projections 32a at the periphery at which the diaphragms are supported and pleats 32b which project outwardly from the outer faces of the diaphragms at the periphery of said faces to such an extent that the top of each pleat is located somewhat beyond the outer faces of respective frame members 29.

Said frame members 29, spacer 30, partition 31 and diaphragms 32 are tightly connected by suitable means

such as bolts or the like (not shown) in one body. The outer faces of the pair of diaphragms 32 have numerous projections to form the cloth-supporting beds 3a and 3b. Filtrate passages 32c among such numerous projections are communicated to a pair of filtrate-recovering passages 34 which are perforated through the frame members 29. Closed compartments 35 formed behind the diaphragms 32 between the diaphragms and the partition 31 are communicated to a supply path 36 for compressed fluid which is provided through the spacer 30 and partition 31.

Each filter plate 3 is provided with a fluid passage 37 communicating with the closed compartments 35 at the lower portion of the plate, a slurry passage 38 at the upper portion of the plate which penetrates the frame members 29 and the spacer 30, and recesses 40 at both surfaces of the plate which are formed around the slurry path 38 and into which respective slurry-feeding devices 39 shown in FIG. 7 are inserted with interposing respective filter cloths 11A and 11B between the plate and the devices when the filter plates are assembled.

The slurry-feeding device 39 has a slurry passage 42, which is to be communicated to said slurry passages 38 of the plates 3 and slurry passages 41 perforated through the filter cloths 11A and 11B at the upper portions thereof, and a feed passage 43 which extends from the slurry passage 42 downwardly so as to open between the cloth 11B covering the rear bed 3b of a particular plate 3 and the cloth 11A covering the front bed 3a of the next rearward plate 3. As shown in FIGS. 7 and 11 the feeding device 39 employed in the filter press of this embodiment is composed particularly of a pair of plate-like members 39a and 39b which are pivotally connected to each other at the top 44. The members 39a and 39b have grooves 43a and 43b respectively with which said feed passage 43 is formed. Respective plate-like members 39a and 39b are secured to the adjacent filter cloths 11A and 11B at the portions below the upper cloth-supporting bars 12 by screws 45a and 45b, respectively.

A guiding roll 46 is provided below each filter plate 3 which is rotatably supported by the brackets 16 and which has a diameter larger than the thickness of the plate so that the roll 46 gives, when the filter plates are separated, some clearance between the cloths 11A and 11B and the adjacent plates so as to travel the cloths without being in contact with the surfaces of the plates. The guiding roll 46 has a resilient outer layer of sponge or the like so that, even when the plates 3 are assembled, adjacent rolls 46 below adjacent plates 3 will not interfere with each other owing to the deformation of the same, as shown in FIG. 8.

Below the guiding rollers 14 and 15 are provided scrapers 47 and 48 which confront the outer surfaces of the filter cloths 11A and 11B around the rollers, respectively. The scrapers 47 and 48 scrape off cakes from the filter cloths 11A and 11B, as will be detailed later with reference to FIG. 10. Brush rolls or the like may be used as cakes-discharging means in place of such scrapers. Further, below each plate 3 are provided washing tubes 49, 50 and 51 which have numerous nozzles facing the cloths 11A and 11B and which are communicated to a source of washing water through flexible pipes (not shown in the drawings).

The filter press of the present embodiment operates as follows. When the cloths 11A and 11B are located

to such level shown in FIG. 2 and then the filter plates 3 are assembled, the slurry passages 38, 41 and 42 form a passage along a line through the filter plates 3, the slurry-feeding device 39 and the filter cloths 11A and 11B disposed between each adjacent filter plates 3 are supported by the respective beds 3a and 3b on the diaphragms 32 respectively. In this case, the guiding rolls 46 are deformed as shown in FIG. 8. Then, when liquid to be filtered or slurry is fed into the slurry passages 38, 41 and 42 under pressure, said liquid or slurry is fed from the feed passages 43 of the device 39 to between the cloths 11A and 11B disposed between each adjacent plates 3 and then is filtered by the cloths.

Filtrate flows through the filtrate passages 32c into the spaces between the diaphragms 32 and the frame members 29 and then into the filtrate-recovering passages 34. Between each adjacent filter cloths 11A and 11B are accumulated cakes 52 which adhere to the outer surfaces of each adjacent cloths 11A and 11B with a hollow remaining in the form of a convex lens, as shown in FIG. 9a. Supply of slurry is stopped when the cakes 52 have accumulated considerably and the filtering rate becomes reduced. Compressed liquid such as compressed water is then supplied into the closed compartments 35 through the fluid passage 36, whereby respective cakes 52 on the filter cloths 11A and 11B are pressed by the diaphragms 32 and further discharge filtrate. Cakes 52 are thus de-watered to form a thin board of cakes between each adjacent filter cloths, as shown in FIG. 9b. The fluid passage 37 is then communicated to a source of compressed air (not shown) so as to discharge liquid in the compartments 35, and then said air is discharged from the compartments 35 so as to recover the diaphragms 32 to original postures.

The filter plates 3 are then separated all at once to give definite intervals therebetween, as shown in FIG. 2. In this case, the guiding rolls 46 recover their original cylindrical shapes and the filter cloths 11A and 11B are brought apart from the cloth-supporting beds 3a and 3b of the plates 3 to become located again at positions shown in FIG. 2. Thereafter, each driven shaft 19 is rotated by the driving shafts 27 into the counterclockwise direction in FIG. 2 so that each upper cloth-supporting bar 12 is lowered and each lower cloth-supporting bar 13 is raised. In this case, filtration-operating areas of the cloths 11A and 11B, namely portions of the cloths carrying cakes 52 thereon pass or are turned round the guiding rollers 14 and 15 along U-shaped paths so that cakes 52 having adhered to the cloths 11A and 11B are scraped off by the scrapers 47 and 48 to drop downwardly, as shown in FIG. 10.

The portions of the pairs of cloths 11A and 11B having cakes removed therefrom leave the guiding rollers 14 and 15 to travel upwardly through clearances between the plates in such a manner that the outer surface of one cloth in said pair or the surface of said one cloth having carried cakes is always covered by the other cloth of said pair. As a result, contaminations possibly remaining on said outer surface of each cloth will not contaminate the surfaces of each plate 3.

The travel of the filter cloths 11A and 11B is stopped when the filtration-operating areas of said cloths have just left the edges of the scrapers 47 and 48. In this lowered or descended state of the cloths 11A and 11B, each slurry-feeding device 39 is lowered or descended to its lowermost position shown in FIG. 11. The plate-

like members 39a and 39b of said device become opened automatically as shown so that the slurry passage 42 and feed passage 43, which is separated into grooves 43a and 43b, can be washed by jetting washing water from the nozzles of the washing tubes 49, 50 and 51.

Upon the completion of the cake-removing operation and washing of the slurry-feeding device 39, the driving shafts 27 are rotated in the reverse direction to rotate the driven shafts 19 in the clockwise direction in FIG. 2, and washing water is sprayed toward the cloths 11A and 11B from the nozzles of the washing tubes 49, 50 and 51. In this case, the filter cloths 11A and 11B are travelled into the reverse direction and are washed with washing water from the tubes on the way of such return travel of the cloths. The filter press is ready to be used for a further filtering operation when the filter plates 3 are assembled again after the cloths have been returned to their original positions shown in FIG. 2.

The structure of the filter plate employed in the filter press of the first embodiment detailed above, in which cloth-supporting beds of the plate are formed with diaphragms which may be expanded or pushed outwardly by supplying compressed fluid behind the same, is advantageous in that cakes formed between the filter cloths can be pressed to obtain highly de-watered cakes and cakes can be withdrawn very smoothly, even if the clearances between the filter plates are small, from between the filter plates by reducing the thickness of said cakes. This makes the press compact, and the filtering capacity of the press large. Further, the slurry-feeding device 39 employed in the filter press of the first embodiment may be washed, even when narrow passages in the device are choked by fibrous material in the slurry, by opening the device automatically during the cake-discharging operation as shown in FIG. 11 and detailed before so that the slurry-feeding device will avoid such problems as choking. This contributes to the automatic and unmanned operation of the press.

Turning now to a consideration of FIGS. 12 through 16, there is shown another embodiment of the filter press according to the present invention wherein like parts are designated by like numerals used in FIGS. 1 through 11. Similarly to the press of the first embodiment, a plurality of recessed filter plates 3 are arranged between a fixed head 4A and a movable head 4B in such a fashion that the plates 3 and the movable head 4B are slidably mounted by means of arms 5 at both sides on a pair of guiding rails 1 bridged between front and rear machine frames 2, as shown in FIG. 12. In contrast to the filter plates employed in the press of the first embodiment, the filter plates 3 employed in the filter press of this second embodiment may be separated one by one successively by a separating means (not shown) which is employed in conventional and known presses. When the movable head 4B is pushed by a hydraulic cylinder unit 10, said filter plates 3 are assembled with holding filter cloths 11A and 11B between two adjacent plates 3. The filter plates 3 employed in the press of this embodiment have no diaphragms for pressing cakes, which are employed in the press of the first embodiment, but have conventional constructions. If desired, however, such diaphragms may also be employed.

In the filter press of this embodiment, the filter cloths 11A and 11B are not supported by the filter plates 3 but are supported by separate gate-like supporting

frames 60 which are arranged between the front and rear machine frames 2. Each of said supporting frames 60 is slidably mounted between two adjacent plates 3 on the guiding rails 1 by means of arms 61 which are projected laterally from the frame 60 at both sides. Thus alternately arranged filter plates 3 and supporting frames 60 are connected by a series of links 62 in such a manner that each supporting frame 60 becomes located outside each face of contact between two adjacent plates 3 when the plates are assembled by pushing the head 4B by means of the cylinder unit 10. The frame 60 becomes located between and outside the two adjacent plates 3 when said two plates are separated from each other by such an extent that the links 62 permit.

As shown in FIGS. 13, 14 and 15, each of the supporting frames 60 supports a pair of filter cloths 11A and 11B. Cloth 11A covers the front cloth-supporting bed 3a of a filter plate 3 and the other cloth 11B covers 20 the rear cloth-supporting bed 3b of the next forward filter plate 3. To the upper edges of said pair of filter cloths 11A and 11B are secured a pair of upper cloth-supporting bars 12A and 12B, respectively. The pair of filter cloths 11A and 11B are trained over a pair of 25 guiding rollers 14 and 15, which are rotatably supported by the supporting frame 60, in such a manner that the cloths 11A and 11B are brought apart from each other. The lower edges of said cloths 11A and 11B are supported respectively by a pair of lower cloth-supporting bars 13A and 13B which are located above 30 the rollers 14 and 15 and are secured to said lower edges. Thus, filter cloth 11A covering front bed 3a of one filter plate 3 and filter cloth 11B covering rear bed 3b of the filter plate are trained over guiding rollers 14 and 15 supported by forward and rearward supporting frames 60 in such a manner that said cloths 11A and 11B are brought or come close to each other. The levels of guiding rollers 14 and 15 supported by one supporting frame 60 are made different from each other, 35 as shown in FIG. 13.

For the purpose of holding the location of the cloths 11A and 11B and travelling said cloths upwardly and downwardly through the clearance between separated two adjacent filter plates 3, driving means for each pair of cloths 11A and 11B are connected to said cloth-supporting bars 12A, 12B and 13A, 13B. Said means include a driven shaft 19 which is supported by the upper portion of each supporting frame 60 and on which two pairs of winding drums 63 and 64 are fixedly mounted at both sides. To the upper cloth-supporting bars 12A and 12B supporting the upper edges of the filter cloths 11A and 11B are connected, respectively, thin belts 65A and 65B of a synthetic resin which are wound around the drums 63 in the clockwise direction and are fixed to said drums at the ends. Similarly, to the lower cloth-supporting bars 13A and 13B supporting the lower edges of the filter cloths 11A and 11B are connected, respectively, thin belts 66A and 66B of a synthetic resin which are wound around the drums 64 in the counterclockwise direction and are fixed to said drums at the ends.

The supporting frame 60 is further provided with rollers 67 for guiding the belts 66B toward the required direction and means for driving the shaft 19 mounting the drums 63 and 64. That is, as shown in FIGS. 13 and 14, the shaft 19 fixedly mounts at one end a bevel gear 25 which meshes with a bevel gear 26 mounted rotat-

ably on a driving shaft 27. Between the driving shaft 27 and the bevel gear 26 is arranged an electromagnetic clutch 68. By operating said clutch 68, the shaft 19 may be rotated into one or the other direction by a required degree. Thus, when the shaft 19 is rotated into one or the other direction, the bars 12A and 12B supporting the upper edges of the pair of cloths 11A and 11B and the bars 13A and 13B supporting the lower edges of the pair of cloths 11A and 11B are moved upwardly and downwardly in a seesaw-like manner through the belts 65A, 65B and 66A, 66B which are wound around the drums 63 and 64 so that the pair of filter cloths 11A and 11B are travelled at one upwardly and downwardly with passing round the guiding rollers 14 and 15.

Therefore, when the shaft 19 is rotated into counter-clockwise direction in a state where one of the supporting frames 60 is separated by definite intervals from the forward and rearward filter plates 3 as shown in FIG. 13, filtration-operating areas of the pair of filter cloths 11A and 11B which have covered the beds 3a and 3b of said rearward and forward plates 3, respectively, are descended or lowered once, are moved round the guiding rollers 14 and 15 with facing cake-carrying surfaces outwardly so as to become apart from each other, and are raised again after leaving the rollers 14 and 15.

The supporting frame 60 is further provided at the lower portion thereof with scrapers 47 and 48, which are faced respectively to the guiding rollers 14 and 15 across the cloths 11A and 11B, and washing tubes 69, 70, 71 and 72 having a number of nozzles for supplying washing water to the filter cloths.

Each supporting frame 60 also supports a slurry-feeding device 73 having a pipe 74 and a nozzle means 75 which is to be located between the cloths 11A and 11B. Said nozzle means 75 connected to the pipe 74, which is communicated to slurry source through a flexible pipe (not shown), is tightly held between assembled forward and rearward filter plates while being located between the cloths 11A and 11B. Each filter plate 3 is provided at both surfaces with recesses into which forward and rearward nozzle means 75 are inserted in a liquid-tight manner respectively.

The filter press of the present embodiment operates as follows. During a filtering operation, the filter cloths 11A and 11B are kept at the uppermost location. That is, the upper cloth-supporting bars 12A and 12B supporting the upper edges of the cloths 11A and 11B are located at the uppermost position shown, and the lower cloth-supporting bars 13A and 13B supporting the lower edges of said cloths 11A and 11B are located below the filter plate 3 so that filtration-operating areas of said cloths are located in face-to-face relation to the cloth-supporting beds 3a and 3b of each filter plate 3. Also, respective nozzle means 75 of the slurry-feeding device 73 are interposed between respective adjacent filter plates 3 and the filter plates 3 are assembled. In this case, respective supporting frames 60 supporting the filter cloths 11A and 11B are brought outside the face of contact of respective adjacent filter plates 3.

Therefore, when liquid to be filtered or slurry is fed by the nozzle means 75 of the feeding device 73 under pressure between the pair of filter cloths 11A and 11B which are supported by the frame 60 and also by the supporting beds 3a and 3b of the plates 3, said liquid or slurry is filtered so that filtrate is withdrawn toward filtrate-recovering passages 76 formed in the plates 3 and cakes 52 are accumulated between the filter cloths 11A

and 11B. When the cakes 52 have accumulated considerably and result in a reduced rate of filtration, feeding of slurry is stopped, and the filter plates are separated one by one successively. At the same time, the frames 60 supporting the pair of filter cloths 11A and 11B are separated from the plates 3 one by one successively to give definite intervals between the frames and adjacent two filter plates. Then, the filter cloths 11A and 11B are travelled. By such operation, cakes 52 accumulated between the cloths 11A and 11B can be scraped off easily from the surfaces of the cloths 11A and 11B and both surfaces of said filter cloths may be washed.

That is, when the shaft 19 is rotated in a clockwise direction by operating the electromagnetic clutch 68 so as to rotate the driving shaft 27 into positive direction by a definite degree of rotation, the pair of filter cloths 11A and 11B are travelled in such direction that the upper edges of said cloths become descended or lowered and the cloths 11A and 11B pass around the pair of guiding rollers 14 and 15 so as to become apart from each other. Because of the travel of the filter cloths 11A and 11B, cakes 52 accumulated between the cloths and adhered to the surfaces of said cloths are descended together with the filter cloths 11A and 11B and are scraped off by the scrapers 47 and 48 when the cloths 11A and 11B pass round the guiding rollers 14 and 15, as shown in FIG. 16.

The filter cloths 11A and 11B from which cakes 52 have been removed leave the guiding rollers 14 and 15 in such a manner that the edges to which the lower cloth-supporting bars 13A and 13B are secured are raised or moved upwardly. Said travel of the filter cloths 11A and 11B is stopped when the filtration-operating areas of said cloths or surfaces of the cloths carrying cakes 52 thereon have passed or left the scrapers 47 and 48. Then, the cloths 11A and 11B from which cakes have been scraped off are travelled or moved into the reverse direction by rotating the driving shaft 27 reversely by a definite degree of rotation. At the same time washing water is supplied to each of the washing tubes 69, 70, 71 and 72, whereby the cloths 11A and 11B are washed with said water coming from the tubes, and the filtration-operating areas of said cloths are returned to their original positions.

In the filter press of the second embodiment shown in FIGS. 12 through 16 and detailed above, each of a pair of filter elements which are provided to a filter plate 3 comprises a filter cloth 11A or 11B which covers front or rear cloth-supporting bed 3a or 3b of said plate, upper and lower cloth-supporting bars 12A, 13A or 12B, 13B which are secured respectively to the upper and lower edges of said filter cloth, a first pair of belts or flexible elongated driving media 65A or 65B which are connected to both ends of said upper supporting bar 12A or 12B, and a second pair of belts or flexible elongated driving media 66A or 66B which are connected to both ends of said lower supporting bar 13A or 13B. In contrast to the above, in a pair of filter elements which are provided to each filter plate 3 in the filter press of the first embodiment shown in FIGS. 1 through 11 and detailed before, the lower cloth-supporting bars 13A and 13B employed in the second embodiment are made into a common one, namely a lower cloth-supporting bar 13, two pairs of driving media 66A and 66B employed in the second embodiment are made into one pair of flexible elongated driving media, namely, a pair of chains 21 which are con-

nected to said common lower supporting bar 13, upper cloth-supporting bars 65A and 65B supporting the upper edges of filter cloths 11A and 11B covering faced front and rear beds of two adjacent plates employed in the second embodiment are made into a common one, namely an upper cloth-supporting bar 12, two pairs of driving media 65A and 65B employed in the second embodiment are made into one pair of flexible driving elongated media, namely a pair of chains 21 which are connected to said common upper supporting bar 12, and further pairs of flexible elongated driving media connected to said upper and lower supporting bars 12 and 13 are made into common ones, namely, the above stated chains 21 which are trained over sprocket wheels 20 on a driven shaft 19 so that the bars 12 and 13 may be moved upwardly and downwardly in a seesaw-like manner by rotating the shaft 19 into one and the other direction. This simplifies the construction of the pair of filter elements.

The construction of a pair of filter elements which are provided to each filter plate may be changed within the scope of the present invention, and one example of such changes is shown in FIGS. 17 through 20. A pair of filter elements provided to each filter plate in the filter press of this third embodiment are particularly constructed in such a fashion that the lower cloth-supporting bars in said pair of filter elements are made into a common one.

In the filter press shown in FIGS. 17 through 20, each filter plate 3 is constructed in a similar fashion with the one employed in the press of the second embodiment shown in FIGS. 12 to 16. Parts or accessories of the press which are arranged above or below each filter plate are not supported by a separate supporting frame such as the frame 60 employed in the second embodiment but are supported by the lower or upper brackets 16, 18' projected from said filter plates at both sides. The plates 3 may be separated one by one, as shown in FIG. 17. Further, in FIGS. 17 to 20, like parts are designated by like numerals used in the first and second embodiments and are constructed in similar fashions.

Referring to the filter elements and driving means therefor employed in the filter press shown in FIGS. 17 through 20, the upper edges of filter cloths 11A and 11B covering, respectively, front and rear cloth-supporting beds 3a and 3b of each filter plate 3 are supported, respectively, by separate upper cloth-supporting bars 12A and 12B which are secured to said upper edges. The cloths 11A and 11B are trained over guiding rollers 14 and 15 provided below the plate 3 at different levels in such a manner that the cloths 11A and 11B are brought or come close to each other and the other or lower edges of said cloths are supported by a common lower cloth-supporting bar 13. Above each plate 3 are arranged a pair of driven shafts 19A and 19B which are rotatably supported by the brackets 18' at different levels and on which respective pairs of sprocket wheels 20A and 20B are fixedly mounted. Chains 21A which are trained over one pair of sprocket wheels 20A are connected at the respective ends thereof to the upper and lower supporting bars 12A and 13 which support the cloth 11A, whereas chains 21B which are trained over the other pair of sprocket wheels 20B are connected at the respective ends thereof to the upper and lower supporting bars 12B and 13 which support the cloth 11B. The driven shaft 19A is rotated by the other driven shaft 19B through a gear

80B on the shaft 19B and a gear 80A on the shaft 19A, and shaft 19A rotates in the reverse direction as the shaft 19B. The driven shaft 19B is driven to rotate by means 25, 26 and 27 similar to the ones employed in the presses of the first and second embodiments. Between the driving shafts 27 bridged between the front and rear machine frames 2 and each bevel gear 26 is interposed an electromagnetic clutch 68 and, by operating said clutch 68, the shafts 19A and 19B may be rotated at a time selectively into directions reverse to each other by a required amount of rotation. Therefore, when cleaning of the filter cloths 11A and 11B is desired, a filter plate 3 is separated from adjacent front and rear plates 3, as is the case of the filter plate 3 which is located at the right end of FIG. 17, and then the clutch 68 is operated so as to travel the cloths 11A and 11B in such a manner that the upper bars 12A and 12B are lowered and the lower bar 13 is raised. In this case, cakes 52 on the outer surfaces of the cloths 11A and 11B are scraped off by scrapers 47 and 48 when the cloths pass round the guiding rollers 14 and 15. The cloths 11A and 11B are washed with washing water jetted from washing tubes 49', 50' and 51' toward the inner surfaces of the cloths when the cloths are then travelled into the reverse direction. In FIGS. 17 to 20, numerals 81A and 81B designate guiding rollers for the chains 21A and 21B respectively which rollers are supported by the brackets 16 and numerals 82A and 82B designate guiding rollers for the chains 21A and 21B respectively which rollers are supported by the brackets 18'.

The slurry-feeding device 83 which is interposed between each two adjacent filter plates 3 in the press of this third embodiment differs in construction from the devices 39 and 74 employed in the press of the first and second embodiments. That is, as clearly shown in FIG. 20, each slurry-feeding device 83 having a feeding pipe 84 and a nozzle means 85 is supported by a slider 86 which are slidably received by a pair of guiding rods 87 bridged between the front and rear machine frames 2. When the filter plates 3 are assembled, each feeding device 83 or the nozzle means 85 thereof is tightly held between each two adjacent plates while being inserted across the cloths 11A and 11B into recesses which are provided to the front surface of rear plate and the rear surface of front plate. To the feeding pipe 84 of each feeding device 83 is connected a flexible pipe 88 which is communicated to a slurry source (not shown).

Another change in construction of filter elements employed in the filter press which can be made according to the present invention is that, in a filter press wherein filter plates are assembled and separated all at one as is the case of the press shown in FIG. 1, two upper cloth-supporting bars supporting the upper edges of the filter cloths 11A and 11B which cover the front bed 3a of a rear plate 3 and the rear bed 3b of a front plate 3, respectively, are made into a common one 12 and the lower edges of said cloths are supported by separate lower cloth-supporting bars 13A and 13B, as schematically shown in FIG. 21.

Although chains or belts are used in the filter presses of the first to third embodiments detailed hereinbefore as flexible elongated driving media employed in the filter elements, ropes, cords or the like may also be used as such flexible elongated driving media. In FIG. 22, there is shown a part of the fourth embodiment of the filter press according to the present invention wherein

ropes, wires, fibers or the like are used as flexible elongated driving media. A pair of filter elements which are provided to each filter plate 3 are similarly constructed as the ones employed in the press of the third embodiment shown in FIGS. 16 to 19. That is, the lower edges of the filter cloths 11A and 11B covering front and rear beds 3a and 3b of a filter plate 3 are supported by a common lower cloth-supporting bar 13. In this embodiment, two pairs of winding drums 90 and 91 are fixedly mounted on a driven shaft 19 provided above each plate 3. A pair of ropes 92A which are connected to the upper cloth-supporting bar 12A supporting the upper edge of the cloth 11A are wound around the drums 90 in one or a positive direction and are secured to said drums at the ends. A pair of ropes 92B which are connected to the upper cloth-supporting bar 12B supporting the upper edge of the cloth 11B are wound around the drums 91 in one or a positive direction and are secured to said drums at the ends. A pair of ropes 93 which are connected to the lower cloth-supporting bar 13 supporting the lower edges of the cloths 11A and 11B are wound around the drums 90 in the other or negative direction and are secured to said drums at the ends. Thus, the upper supporting bars 12A and 12B and the lower supporting bar 13 are moved downwardly and upwardly in a seesaw-like manner so that the cloths 11A and 11B are travelled downwardly and upwardly with passing round guiding rollers 14 and 15 below the plate 3. Further, in the filter elements employed in the press of this fourth embodiment, the ropes 93 are not connected directly to the lower supporting bar 13 but are connected to said bar 13 through a bar 94 which is connected to the supporting bar 13 through a plurality of bands 95 of a resilient material. Said bands 95 give tension to the cloths 11A and 11B.

In the filter presses of the first to fourth embodiments detailed hereinbefore, filter cloths 11A and 11B of the pair of filter elements provided to each filter plate have such lengths that, when the cloths are in filtration-operating positions or the upper supporting bars or the bar supporting the upper edges of the cloths are or is in uppermost positions or position, the cloths 11A and 11B are once trained by the guiding rollers 14 and 15 below the plate 3 so that the other or lower edges of the cloths are located above the rollers. But, as can be understood easily, the lengths of the filter cloths 11A and 11B may be enough to cover the front and rear cloth-supporting beds 3a and 3b of the plate 3. In FIG. 23 and the following figures, there is shown the fifth embodiment of the filter press according to the present invention wherein the filter cloths are made much shorter than the ones employed in the presses of the hereinbefore detailed embodiments.

As shown in FIG. 23, in the press of this fifth embodiment, the lengths of filter cloths 11A and 11B are somewhat larger than the vertical lengths of the beds 3a and 3b of each plate 3. That is, each of the filter cloths 11A and 11B has such a small length that the cloth is located only at the front or rear of each filter plate 3. The upper edges of the cloths 11A and 11B are supported by upper cloth-supporting bars 12A and 12B which are secured to said upper edges, whereas the lower edges of the cloths 11A and 11B are supported by lower cloth-supporting bars 13A and 13B which are secured to said lower edges. Similarly to the ones of the third embodiment, shown in FIGS. 16 to 19, first pairs

of thin belts 101A and 101B which are connected to the upper supporting bars 12A and 12B are guided upwardly and are supported by a pair of winding drums 63 on a driven shaft 19 above the plate 3. To the lower supporting bars 13A and 13B are connected second pairs of flexible elongated driving media or thin belts 102A and 102B. The belts 102A and 102B are trained over a pair of guiding rollers 14 and 15 below each plate in such a manner that the belts 102A and 102B are brought or come close to one another and are connected to a common bar 110. The bar 110 is connected through a plurality of resilient bands 111 to another bar 112 to which a pair of thin belts 113 are connected. The belts 113 are guided upwardly and are supported by another pair of winding drums 64 on the driven shaft 19 above the plate 3. Of course, said second pairs of belts 102A and 102B may be supported directly by such drums. At any event, in this fifth embodiment also a pair of filter elements provided to each filter plate are trained over a pair of guiding rollers below the plate in such a manner that said elements are brought or come close to each other.

In the construction of the filter elements employed in this fifth embodiment detailed above, the edges of scrapers 47 and 48 may prevent smooth travels of the filter cloths 11A and 11B around the guiding rollers 14 and 15 due to engagement of the lower supporting bars 13A and 13B with the edges of the scrapers. In such a case, the scrapers 47 and 48 may be supported, for example, as shown in FIG. 24 wherein only supporting means for the scraper 47 is shown. Said scraper 47 is pivotally supported at base end thereof and is forced or biased by a spring 104 so that the edge 47a of said scraper is brought into contact with the periphery of of the guiding roller 14. Further, to the scraper 47 is attached an upwardly and outwardly projected cam member 105 which brings the scraper 47 into the position shown in dotted outline in FIG. 24 against the force of spring 104 by being pushed by the lower supporting bar 13A only when said bar 13A passes round the roller 14. Thus, when the driven shaft 19 is rotated into a direction, the lower supporting bars 13A and 13B pass round the guiding rollers 14 and 15 and then are moved upwardly so that filtration-operating areas 100a and 100b of the cloths 11A and 11B are brought successively to the edges of the scrapers 47 and 48, whereby cakes 52 on said areas of the cloths are scraped off, as shown in FIG. 25. Then, when the shaft 19 is rotated into the other direction after said operation for cake-discharging, the filter cloths 11A and 11B are washed with water from washing tubes 114, 115, and so pass round the rollers 14 and 15 without any trouble owing to the displacement of the scrapers into positions such as the ones shown in dotted outline in FIG. 24 and are returned to the original positions shown in FIG. 23.

Having now detailed some preferred embodiments of the filter press according to the present invention by referring to the drawings, each feature particularly disclosed in said embodiments may be substituted or integrally employed so far as no contradiction is resulted.

The most important advantage of the present invention consists in the fact that cakes accumulated on the filter cloths can be removed or discharged very easily, because such cakes are discharged or removed by cake-discharging means such as scrapers, brush rolls,

or the like provided below the filter plates automatically on the way of the travels of the cloths. Another advantage of present present invention consists in the fact that cakes are removed in a time-saving manner, because such cakes-removing is carried out by travelling the filter cloths. A still another advantage of the present invention consists in the fact that cakes are removed very smoothly, because the filter cloths are necessarily moved once downwardly so that cakes on said cloths may be discharged downwardly. In addition, as can be understood now, cakes on the filter cloths may be removed perfectly with ease by said cake-discharging operation.

Another important advantage of the present invention consists in the fact that the filter cloths or cakes thereon never contaminate the filter plates during the cake-discharging operation because the surfaces of the cloths having carried cakes thereon are always in face-to-face relation during the travels of said cloths between each two adjacent filter plates. That is, after leaving the guiding rollers below each filter plate, filter cloths covering front and rear cloth-supporting beds of said plate, respectively, are moved upwardly in such a manner that the surfaces of the cloths having carried cakes are in face-to-face relation to each other so that contaminations still remaining on said surfaces of the cloths never contaminate the surfaces of adjacent plates. Further, in the filter press according to the present invention, washing of filter cloths may be achieved easily by providing washing devices spraying washing water toward the travelling cloths below the filter plates. When such washing devices are so constructed that the devices spray washing water toward the inner surfaces of the filter cloths, very smooth and perfect washing of said cloths can be achieved.

In addition, when the filter elements constructed according to the present invention are combined with filter plates which have diaphragms for pressing cakes, as is the case of the press of the first embodiment shown in FIGS. 1 to 11, cakes formed or accumulated between the filter cloths may be pressed so as to be de-watered, resulting in solidifying and compacting the cakes so that cakes may be withdrawn very smoothly downwardly outside the clearances between the filter plates even if said clearances between the plates are narrow. In this case, therefore, a compact filter press having a larger capacity of filtration may be obtained.

Having now described the invention and having exemplified the manner in which it can be carried into practice, it is apparent to those skilled in the art that innumerable variations, applications, modifications and extensions of the basic principles involved may be made without departing from the spirit of the present invention. The invention is, therefore, to be limited only by the scope of the appended claims.

I claim:

1. A filter press including a plurality of recessed filter plates arranged between front and rear machine frames so that the plates can be assembled and separated, each of said filter plates being provided with a pair of filter elements, each filter element comprising a filter cloth covering one of the front and rear cloth-supporting beds of the plate, upper and lower cloth-supporting bars secured respectively to the upper and lower edges of said filter cloth, a first pair of flexible elongated driving media which are connected to both ends of said

upper supporting bar, and a second pair of flexible elongated driving media which are connected to both ends of said lower supporting bar, one pair of ends of said pair of filter elements being supported respectively through said first pairs of driving media by rotatably supported means which are arranged above the filter plate, and the other pair of ends of said pair of filter elements being trained over a pair of guiding rollers arranged below the filter plate in such a manner that the filter elements are brought close to each other and then are supported respectively through said second pairs of driving media by rotatably supported means which are arranged above the filter plate, driving means for driving said former and latter rotatably supported means in such a manner that the first or second pairs of driving media are pulled down when the second or first pairs of driving media are pulled up, a slurry-feeding device interposed between the filter cloths covering respectively rear and front cloth-supporting beds of each pair of adjacent filter plates, and cake-discharging means below each filter plate for discharging cakes from the surfaces of the cloths on the way of travel of said cloths.

2. The filter press as claimed in claim 1 wherein the filter cloths of each pair of filter elements are supported by a common lower cloth-supporting bar.

3. The filter press as claimed in claim 1 wherein the upper edges of the filter cloths which cover respectively the front cloth-supporting bed of a filter plate and the rear cloth-supporting bed of an adjacent filter plate are supported by a common upper cloth-supporting bar.

4. The filter press as claimed in claim 1 wherein the filter cloths of each pair of filter elements are supported by a common lower cloth-supporting bar and the upper edges of the filter cloths which cover respectively the front cloth-supporting bed of a filter plate and the rear cloth-supporting bed of an adjacent filter plate are supported by a common upper cloth-supporting bar.

5. The filter press as claimed in claim 1 wherein means for tensioning the filter cloths are disposed between said upper cloth-supporting bars and said first pairs of elongated driving media or between said lower cloth-supporting bars and said second pairs of elongated driving media.

6. The filter press as claimed in claim 1 wherein a guiding roll having a diameter larger than the thickness of each filter plate is arranged below each filter plate above said guiding rollers, the roll having a deformable outer layer whereby adjacent guiding rolls do not interfere with each other due to the deformation of the rolls when the filter plates are assembled.

7. The filter press as claimed in claim 1 wherein said cake-discharging means are composed of scrapers, each scraper being faced to one of said guiding rollers.

8. The filter press as claimed in claim 7 wherein each of the filter cloths has such a small length that the cloth is located only at the front or rear of each filter plate, and each of said cake-discharging means is provided with displacing means which displaces said discharging means apart from the periphery of each guiding rollers only when each of said lower cloth-supporting bars passes round said roller.

9. The filter press as claimed in claim 1 wherein washing devices which spray washing water toward the

inner surfaces of the filter cloths during the travels of the cloths are arranged below the filter plates.

10. The filter press as claimed in claim 1 wherein said pair of filter elements are supported by each filter plate by brackets which project from the plate.

11. The filter press as claimed in claim 1 wherein said filter elements are supported by supporting frames which are disposed between the outside each pair of adjacent filter plates and are slidably supported by guiding rails bridged between the front and rear machine frames.

12. The filter press as claimed in claim 1 wherein said first and second pairs of elongated driving media are made into common ones which are trained over said rotatably supported means above each filter plate.

13. The filter press as claimed in claim 12 wherein said elongated driving media comprise chains and said rotatably supported means comprise sprocket wheels over which said chains are trained.

14. The filter press as claimed in claim 1 wherein said elongated driving media comprise belts and said rotatably supported means comprise drums which wind up and off said belts.

15. The filter press as claimed in claim 14 wherein said drums above each filter plate are mounted on a driven shaft arranged above said plate, the belts connected to the upper supporting bars being wound around the drums in one direction and the belts connected to the lower supporting bars being wound

around the drums in the other direction.

16. The filter press as claimed in claim 1 wherein each of said slurry-feeding devices is secured to the upper portions of the filter cloths covering respectively a front cloth-supporting bed of a filter plate and a rear cloth-supporting bed of an adjacent filter plate, the device having a slurry passage and a feed passage running from said slurry passage downwardly and opening between said cloths, said slurry passage being communicated to slurry passages provided to the filter plates and filter cloths when the filter plates are assembled.

17. The filter press as claimed in claim 16 wherein each of said slurry-feeding devices is composed of a pair of plate members which are pivotally connected to each other at the top and which are secured respectively to the filter cloths.

18. The filter press as claimed in claim 1 wherein said slurry-feeding devices are slidably supported by guiding rods which are bridged between the front and rear machine frames and the devices are communicated to a slurry source through flexible pipes.

19. The filter press as claimed in claim 1 wherein each of said cloth-supporting beds of the filter plates is formed with a diaphragm of a flexible material in such a manner that a closed compartment is formed behind said diaphragm, said compartment being communicated to a source of compressed fluid.
